UNITED STATES PATENT OFFICE.

RALPH D. ROSE, OF JOHNSTOWN, PENNSYLVANIA.

RETAINING DEVICE FOR SWITCH-POINTS.

1,333,096.

Specification of Letters Patent.

Patented Mar. 9, 1920.

Application filed July 2, 1919. Serial No. 308,262.

To all whom it may concern:

Be it known that I, RALPH D. ROSE, a citizen of the United States, and resident of Johnstown, in the county of Cambria and 5 State of Pennsylvania, have invented certain new and useful Improvements in Retaining Devices for Switch-Points, of which the following is a specification.

This invention is a retaining device for 10 switch points, and the object of the invention is to provide simple and efficient means for retaining a switch point at each limit of its movement against accidental displacement, while at the same time permitting the 15 usual manual or other operation of the switch point.

It is a further object of the invention to dispense with the use of springs, and to employ in lieu thereof a weight associated with 20 a switch point rod in such a manner as to permit the throw of the switch point from one limit to the other and to retain the switch point at each limit of its movement.

In the drawings—

25 Figure 1 is a side elevation of the switch point retaining device of the present invention, the casing thereof being in section;

Fig. 2 is a plan view of Fig. 1, the cover of the casing being removed;

30 Fig. 3 is a cross sectional view on the line 3—3 of Fig. 1.

For housing and protecting the working parts of the present invention, there is provided a casing 1, preferably in the form of 35 a rectangular cast metal box having a removable top or cover 2. A suitable opening 3 is provided through one side of the box adjacent the top thereof to accommodate a switch point rod 4 disposed in a substantially 40 horizontal position and capable of endwise movement through the opening. That end of the rod 4 which is within the casing is provided with a fork or bifurcation 5 straddling an upright lever 6 and pivotally connected thereto as at 7. The upright lever 6 is fulcrumed intermediate of its ends as at 7 between a pair of bracket arms 8 preferably formed integral with the side of the box or casing 1, at opposite sides of the opening 3.

45 Within the bottom portion of the box there is a substantially horizontal lever 9, fulcrumed intermediate of its ends as at 10 between a pair of upstanding posts or bracket members 11 preferably formed integral with

50 the bottom of the box or casing. A pair of links 12 embracing the lower end of the lever

6 and that end of the lever 9 which is adjacent the switch point rod 4. A suitable pivot pin 13 connects the upper ends of the links 12 with the lower end of the lever 6, 60 and a suitable pivot pin 14 connects the lower ends of the links with the adjacent end of the lever 9. A weight 15 is provided in its bottom with a bifurcation to receive the lever 9, and is further provided with a pair 65 of ears 16 disposed at opposite sides of the bifurcation so as to lie adjacent and at opposite sides of the lever 9. These ears are provided with alined openings for alinement with one of a plurality of openings 17 in the 70 lever 9, and a headed pin 18 is passed through the alined openings so as to retain the weight 15 at an adjusted position upon the lever. A suitable cotter 19, or other detachable means is employed to removably 75 hold the pin 17 in place.

In the operation of the device, the box or casing is placed alongside of the track, and the switch point rod 4 is connected to the switch point in any suitable or desired manner, no connection being shown in the present drawings as the particular form of connection constitutes no part of the present invention. In the position of the parts as shown in Fig. 1 of the drawings, the switch point is at its remote limit, and is retained in this position by reason of the weight 15. When the switch point is moved toward the casing 1, the switch point rod 4 moves into the box, thereby swinging the toggle connection 6—12 from the full line position to the dotted line position, the weight 15 rising until the levers 6 and 12 come into vertical alinement, after which the weight 15 falls and comes to rest in its normal position with 90 the toggle connection at the right hand side of the pivots 7 and 14, whereby the switch point will be retained in its new position and held against accidental displacement.

What I claim is:

1. In a retaining device for switch points, the combination with a switch point rod, of a lever mounted between its ends upon a substantially horizontal fulcrum, an upright lever fulcrumed between its ends and operatively connected to the switch point rod and to said first named lever, and a weight adjustably mounted upon said first mentioned lever.

2. In a retaining device for switch points, the combination with a switch point rod, of a lever mounted between its ends upon a sub-

stantially horizontal fulcrum, an upright lever fulcrumed between its ends and connected to the switch point rod, a link pivotally connecting the levers, and a weight upon the first mentioned lever.

3. In a switch point retaining device, the combination of a casing, a switch point rod working through an opening in the casing, an upright lever fulcrumed between its ends upon a bracket projecting from the casing, a pivotal connection between the upper end of the lever and the switch point rod, a sec-

ond lever mounted between its ends upon a substantially horizontal fulcrum carried by a bracket extending from the side of the casing; a link connection between the lower end portion of the upright lever and one end portion of the second mentioned lever, and a weight carried by the other end portion of the second mentioned lever. 15

In testimony whereof I have hereunto set my hand.

RALPH D. ROSE. 20
